UNITED STATES PATENT OFFICE.

BERNHARD HARTMANN, OF BELLEVILLE, ILLINOIS.

REFRIGERATOR.

SPECIFICATION forming part of Letters Patent No. 333,855, dated January 5, 1886.

Application filed May 1, 1885. Serial No. 164,097. (No model.)

To all whom it may concern:

Be it known that I, BERNHARD HARTMANN, of Belleville, St. Clair county, Illinois, have invented a certain new and useful Improvement in Sectional Refrigerators, of which the following is a full, clear, and exact description, reference being had to the accompanying drawings, forming part of this specification.

Figure 1 is a perspective view with one side 10 and part of the top of the ice-chamber removed. Fig. 2 is a perspective view showing the inner side of one of the sides. Fig. 3 is a horizontal section at 3 3, Fig. 4. Fig. 4 is a vertical section at 4 4, Fig. 3. Fig. 5 is a detail view showing the manner of securing in 15 place the slats which form the bottom of the ice-chamber.

A is the floor of the refrigerator, upon which stand the inner and outer walls. 20 B is a water-channel made in the floor, just within the inner wall, to prevent the water of condensation escaping between the floor and the walls in such a manner as to make damp the sawdust or other packing with which the 25 space between the inner and outer walls is filled. The water-channel B leads to a drain-pipe, C, which is let into the floor and extends from the channel to the outer side of the outer wall, where the water may have free exit 30 or escape through a trap, D, as shown, to prevent the entrance of air. The inner wall is composed of four sections, E and E'. The wall-sections E are made with cleats F near to the upright edges of the sections, thus forming 35 a rabbet-groove at each of these edges, in which the corners of the sections E' rest. The sections E and E' are secured together at the corners in any suitable manner. For this purpose I show hooks and eyes G and H, attached to the different sections, respectively. 40

The sections are strengthened or stiffened by ribs I and J, secured to the outer sides, and the upright ribs I are fastened to similar ribs, I', upon the inner sides of the outer walls by 45 means of hooks K and eyes L, or by any other suitable means. The outer walls are composed of sections arranged in much the same manner as the inner walls, there being a space, M, between the walls, which is filled with 50 sawdust or any other suitable packing to check the entrance of heat into the inner chamber, N.

O is a cover which is secured by screws or other means to the top of the walls E E', so as to form a top to the ice-chamber P. The bottom of the ice-chamber is composed of 55 slats or bars Q, upon which the blocks of ice are placed and between which the cold air and water descend into the chamber N, which contains the articles to be kept cool. These slats are dovetailed at their extremities into 60 the horizontal supporting cleats Q', whereby said slats are not only held against displacement themselves, but aid materially in bracing and holding the side sections, E E'. The outer walls consist of sections R and R', fitted 65 together at the corners, and there secured by hooks S and eyes T, or by any other suitable means.

U and V are hinged doors closing doorways in one of the walls E, and U' V' are doors in 70 the outer wall's section S, in line with the doors U and V, respectively. By means of the doors U U' access is had to the chamber N, and by the doors V V' to chamber P.

The wall-sections E E' R R' are described 75 and shown as each consisting of a single part; but where the refrigerator is of considerable size each of these wall-sections may be made of two or more parts connected by vertical joints. 80

These refrigerators are, it will be seen, portable, and they are intended for a more or less temporary use. By this construction the parts may be readily separated and conveniently transported from place to place. 85

I claim—

1. A refrigerator having an inner and outer case, whose upright walls are composed of sections engaged together at the vertical corners, and having stiffening-ribs I and I' between the corners, engaged together, substantially as set forth. 90

2. An inner case having wall-sections E E', and containing lower chamber, N, and ice-chamber P, an outer case having wall-sections 95 R R', and a floor having a water-channel communicating with a discharge-pipe extending from the inner chamber to the outside of the refrigerator.

3. The two cases E E' and R R', one within 100 the other, and the lower and upper openings through the sides of the cases, with doors U U'

and V V', closing in the planes of the sides, substantially as set forth.

4. The combination of bottom A, an inner and outer case, E E' and R R', standing upon 5 the same, cover O, and doors U U' R R', substantially as set forth.

5. In a refrigerator, an ice-chamber having a floor composed of slats dovetailed at their ends into their supports, substantially as set 10 forth.

6. In a knockdown refrigerator, the combination, with the opposite removable sides E E', of the slats Q, connected therewith by means of dovetail joints, as set forth.

BERNHARD HARTMANN.
